PILOT FLAME CONTROL FOR
FUEL BURNERS

Woods Stockton Walker, Great Neck, N. Y., assignor to Consolidated Edison Company of New York, Inc., New York, N. Y., a corporation of New York

Application April 10, 1946, Serial No. 661,028

3 Claims. (Cl. 158—117.1)

1

This invention relates to apparatus for controlling a pilot flame of a fuel burner, and more particularly to pilot flame control means for a gas furnace.

Heating apparatus such as those employed for heating houses, for example of the gas burning variety, usually are provided with a master gas control valve on the gas supply main for the purpose of shutting off the gas supply when the use of the furnace is to be discontinued for an appreciable period, such as the summer season. The closing of such a valve, in some types of heating apparatus heretofore employed, shuts off the supply of gas not only to a main burner of the furnace but also to a pilot flame in the furnace. Certain other types of heating apparatus heretofore used have been provided with a separate pilot valve control which is not affected by the opening or closing of the master valve because the pilot gas conduit is connected, for example, upstream relative to the master valve.

It is desirable that the users of such apparatus themselves shall be able to turn on and off their furnaces. This involves no substantial difficulties with regard to the turning off of the fuel. However, with respect to turning the fuel on again, difficulties arise with large numbers of users because of their reluctance or inability to light the pilot flame. In fact, it has been found to be true, especially in large metropolitan areas, that the average furnace user not only requests and expects the fuel or gas company to turn on his fuel whenever it is so desired, but also to turn it off. Thus, in the spring and again in the fall large numbers of furnace users make heavy demands upon fuel companies for such services.

It has been necessary in the past for companies providing fuel, such as gas or oil, to maintain service staffs which devote their time to the turning off and on of the fuel, and to the extinguishing and igniting of pilot flames in furnaces, especially in the spring and fall.

The maintenance of staffs for the above purposes constitutes an added expense which must be passed on to the users of the furnaces. In addition to the expense of this method for starting and discontinuing the operation of furnaces, there is usually the inconvenience of delay between the time a request is made for this service and the time of compliance.

In heating apparatus heretofore employed a disadvantage has existed in that during periods of non-operation of the furnace, such as the summer, the pilot flame is totally extinguished. The temperature within the furnace thus often

2

falls below the dew point and a strong tendency arises for the metal surfaces of the furnace to rust or corrode. This is especially true in damp cellars where furnaces are often located.

Furthermore, apparatus heretofore employed for starting pilot flames have been expensive to manufacture and maintain.

According to the present invention, apparatus is provided for controlling a pilot flame for a furnace which will eliminate the above noted difficulties.

Various further and more specific objects, features and advantages of the invention will clearly appear from the detailed description given below taken in connection with the accompanying drawing which forms a part of this specification and illustrates, by way of example, preferred arrangements of apparatus for carrying out the invention. The invention consists in such novel combinations of features and apparatus as may be shown and described in connection with the equipment herein disclosed.

In the drawings:

Fig. 1 is a schematic diagram of one form of apparatus for carrying out the invention; and

Fig. 2 is a view partly in section and with parts broken away showing a novel embodiment of a pilot control valve and main fuel control valve.

Referring to the drawings in further detail, simple and inexpensive means are provided which enable a furnace user personally to turn on and off his furnace comprising a main valve and a pilot flame control valve. The user by these means may easily turn down the pilot flame to a small and economical size during extended periods when no heat is required, and he may personally turn the pilot flame to its full operating size at other times without aid from a fuel company or any servicing agency.

The average pilot flame for furnace burners may consume gas at a rate of approximately five cubic feet per hour when of full size. At this rate a pilot flame, which burns during an average summer season, may consume enough gas to involve substantial expense to the user. If the pilot flame is reduced to a point where it is as small as possible, and still constitutes a stable flame, the amount of gas consumed during an average summer season may be reduced by as much as two-thirds.

Generally, according to prior practice, during a summer season the pilot flame is turned off entirely and the furnace is shut down, the cost for maintaining a full pilot flame being thereby avoided. However, in order to provide the con-

venience of having heat whenever it is desired without the delay of waiting for a service agency, a reduced pilot flame may be maintained with the present invention at a nominal cost, entirely acceptable to most furnace users.

In the embodiment shown in Fig. 1 means are provided for producing a full pilot flame during normal operation of a gas furnace, and for providing a reduced or small pilot flame when it is desired to discontinue the operation of the furnace seasonally or at any other time. The reduced pilot flame which burns continually constitutes the means for lighting the full pilot flame.

A fuel burner, for example, of the gas burning type, of well-known design is provided at 10 having a burner element 11 which is in communication by means of a conduit 12 with a suitable source of fuel (not shown). A conventional main shut-off or primary control valve may be provided at 13. The latter is normally maintained in an open position but may be employed for shutting down the furnace.

A secondary fuel control valve, also of conventional design, may be provided at 14 and is adapted by means to be hereinafter described, intermittently to open and close in a well-known manner in response, for example, to room temperature.

The secondary control valve 14 may be operatively connected in a known manner to, for example, two different heat-responsive means. In the embodiment shown, valve 14 is connected to a room thermostat 15, and to a second thermostat which is variously termed as a furnace thermostat, a pilot flame thermostat, or a safety thermostat. The latter may constitute, for example, a bi-metallic strip which opens or closes a valve control electric circuit 17, 18 in response to heat applied thereto. Thermostat 16 is adapted to be actuated by a predetermined minimum amount of heat. In a manner to appear hereinafter it is actuatable by said full pilot flame but not by the reduced flame. Said circuit is connected to a suitable source of electric energy (not shown) by means of leads L₁, L₂. The above-mentioned operative connection between valve 14 and the thermostats 15 and 16 may comprise the circuit 17, 18, and a solenoid 19 in the circuit which, when energized, is capable of moving a suitable valve control arm 20 against the action of a spring 21 to open valve 14.

A pilot flame conduit or tube 22 is provided having a nozzle or burner 23 which is preferably adjacent the furnace thermostat 16. The pilot flame tube is in communication with conduit 12 at a point 22' which is disposed upstream relative to the valve 13.

Novel means are provided for controlling said pilot flame, which means are extremely simple of operation and are adapted for personal manual operability by the furnace user, whereby a full flame may be produced and controlled during normal operation of the furnace, and a reduced pilot flame of economical size may be easily obtained and maintained during periods of seasonal non-use of the furnace. In the form shown in Fig. 1, the novel means comprise a pilot control valve 24, around which a by-pass 25 is provided. Fluid flow through the latter preferably is adjustable, for example, by a suitable piston type valve capable of fine adjustment by angular movement of a threaded screw. Such adjusting means may be located at 26. A small amount of fuel thus may flow to the nozzle 23 at all times even though the main pilot control valve 24 is closed. This small

amount of fuel is sufficient to provide the reduced pilot flame above discussed.

In operation, when the furnace is in normal use both main valve 13 and pilot valve 24 are in open positions. The pilot flame at 23 is at its full size. The heat from the full pilot flame is sufficient to actuate the heat-responsive means 16 thereby closing at that point the electric circuit 17, 18. The flow of fuel through conduit 12 thus is controllable in a well-known manner by the thermostat 15 in cooperation with valve means 14 and the solenoid 19. When it is desired to suspend the operation of the furnace for a considerable period, such as the summer season, the valve 13 preferably first is closed. The pilot flame at 23 is still at its full size. Circuit 17, 18 is, therefore, closed at the thermostat 15 and valve 14 is operable in its usual manner by the thermostat 15 even though no gas may flow to the furnace.

The pilot control valve 24 is next closed. The main flow of fuel to the pilot flame consequently is shut off. However, a sufficient quantity of fuel flows via the by-pass 25 to maintain a small but stable flame at the nozzle 23. The small flame is not of sufficient intensity to actuate heat-responsive means 16. Consequently, the circuit 17, 18 is promptly opened. During the period when only the small flame burns it is, therefore, impossible for the solenoid 19 to be energized. Consequently the control arm 20 of valve 14 is withdrawn to a closed position by the action of spring 21, and the room thermostat 15 is ineffective to control the furnace. During this period the heat from the reduced pilot flame is sufficient to maintain a temperature within the furnace in excess of the dew point and thus serious corrosion may be avoided.

When it is desired to put the furnace back in operation, for example, at the end of the summer season, the above procedure is reversed. First, the pilot valve 24 is opened, thereby producing a full pilot flame, the intensity of which actuates the thermostat 16 and renders operable the valve control solenoid 19 and the valve 14. Next, the main valve 13 is opened and the furnace now is able to operate in its normal manner in response to the thermostat 15.

If desired, a suitable mechanical linkage or interlock of known form, between the main control valve and the pilot flame valve may be provided in order to prevent shutting the pilot valve until the main valve has been closed, and to prevent opening the latter until after the pilot valve is opened.

In order to simplify the operation of turning on and off the gas furnace and to provide automatically for the increase or reduction in the pilot flame substantially simultaneously with the time of turning on or off respectively of the main gas supply, novel integral main and pilot control means may be provided according to the embodiment shown in Fig. 2 which comprises a valve 27 having a housing 28, an inlet 28a, and an outlet 28b. A rotatable valve member 29 is provided in said housing having a main channel 30 therethrough and a pilot fuel channel 31. The latter is preferably substantially perpendicular to channel 30 and is in communication with pilot conduit 22 by means of a channel 32 which, for example, is in direct connection with a pilot flame by-pass channel 33. Channel 32, however, may be in direct connection with conduit 22. The extremity of channel 31 which is in register with channel 32 in Fig. 2 is closed off entirely by hous-

ing 28 when rotatable valve member 29 is angularly shifted an amount sufficient to move said extremity out of register with channel 32.

By-pass channel 33 and channel 32 are preferably formed in the housing 28. Channel 33 has an inlet at 33a, and an outlet 33b. By-pass inlet 33a is in communication with valve inlet 28a and is upstream relative to rotatable valve member 29. Conduit 22 may be connected at 33b.

Suitable means are provided for manually rotating the valve member 29 comprising a handle 34 which is preferably fixed directly to said valve member.

In order to make fine adjustments of fuel flow through the by-pass channel 33, a suitable by-pass valve of, for example, the piston type is provided at 35 which may be adjusted by angular movement of threaded member 35a.

In operation, in the angular position of the rotatable valve member 29 shown in Fig. 2, the fuel is able to flow freely from inlet 28a through the main channel 30 of valve member 29 to outlet 28b and thence to the furnace via conduit 12. Fuel for the pilot flame reaches conduit 22 not only through the by-pass 33 but also through the channels 31 and 32. Flow through the channels 31 and 32 is, of course, the main source of pilot flame fuel. A full pilot flame is thus sustained. If it is desired to shut off the furnace, for example, for the summer, the handle 34 is angularly shifted through 90 degrees in a clockwise direction. Thus in a single motion, and substantially simultaneously, the main fuel flow to the furnace and to the pilot flame are stopped. Only a restricted amount of gas may now flow to the pilot flame through by-pass 33 in a quantity sufficient to produce a small but stable flame. The intensity of the latter is, as above mentioned, insufficient to actuate the safety thermostat 16 which promptly cools and opens the circuit 17, 18 thus causing the secondary valve 14 to shut off the main gas supply to the burner. In this condition both the primary and secondary gas control valves (27 and 14 respectively) are closed thus providing additional safety against gas leakage into the furnace or accidental operation thereof.

A reverse procedure is followed for starting the furnace in operation. The handle 34 is reversed in movement to the position as shown in Fig. 2. The full pilot flame is thus immediately produced without the necessity for ignition by some separate means. In case the full pilot flame fails to come on for any reason, thermostat switch 16 will remain open and valve 14 will remain closed.

The novel pilot flame control has been described in connection with a gas furnace. However, it may be employed in any type of furnace burning a fuel which is adapted for ignition by a pilot light, for example, an oil burning furnace.

While the invention has been described with respect to certain preferred examples which have given satisfactory results, it will be understood by those skilled in the art after understanding the invention that various changes and modifications may be made without departing from the spirit and scope of the invention, and it is intended, therefore, in the appended claims, to cover all such changes and modifications.

What is claimed as new and desired to be secured by Letters Patent is:

1. In apparatus of the class described, a main gas conduit, a gas burner, a primary control valve

in said conduit, a secondary control valve in said conduit, a pilot fuel conduit operatively associated with said burner, a pilot flame burner connected to said pilot conduit, a pilot flame control valve in said pilot fuel conduit for controlling a full pilot flame, by-pass means around said pilot flame control valve permitting a restricted flow of gas for sustaining a small pilot flame, heat-responsive means adjacent said pilot flame burner, and electrical means operatively connected to said heat responsive means and to said secondary control valve for controlling the latter by said heat-responsive means, the latter being actuatable by said full pilot flame only.

15 2. Apparatus of the class described, comprising a fuel burner, a main fuel conduit to the burner, fuel flow control means in said conduit, a pilot conduit for feeding fuel to a pilot flame for said burner, a pilot flame burner connected to said pilot conduit, heat-responsive means operatively associated with said pilot flame burner and said fuel flow control means, the heat responsive means being operatively associated with said fuel flow control means by electrical means, and mechanism in the pilot conduit for adjusting the pilot flame to a full size and to a small size, said heat-responsive means being actuatable by a pilot flame of full size only.

20 3. Apparatus of the class described, comprising a fuel burner; a main fuel conduit connected to said burner; primary fuel control means for said conduit; secondary fuel control means for said conduit; a plurality of heat-responsive elements; electrical means for operatively interconnecting said elements and said secondary fuel control means; a pilot tube having a pilot burner at which a pilot flame can burn for said first-mentioned burner, said pilot burner being positioned adjacent to one of said heat-responsive elements, the latter being actuatable by a flame at said pilot burner; valve means in the pilot tube, said valve means when open permitting a full pilot flame fuel flow; and by-pass conduit means around said valve means permitting a continuous small pilot flame fuel flow, said heat-responsive element adjacent said pilot burner being actuatable by a full pilot flame only.
